UNITED STATES PATENT OFFICE

132,652

DESIGN FOR A BROOCH OR SIMILAR ARTICLE

Eileen Dixon, Miami, Fla.

Application April 3, 1942, Serial No. 106,446

Term of patent 3½ years

To all whom it may concern:

Be it known that I, Eileen Dixon, a citizen of the United States of America, residing in Miami, county of Dade, and State of Florida, have invented a new, original, and ornamental Design for a Brooch or Similar Article, of which the following is a specification, reference being had to the accompanying drawing, forming part thereof.

Fig. 1 is a front view of a brooch or similar article showing my new design.

Fig. 2 is a side view thereof.

Fig. 3 is a rear view of Fig. 1.

I claim:

The ornamental design for a brooch or similar article, substantially as shown.

EILEEN DIXON.
